FLEXIBLE PANEL JOINING MEANS

George F. Reitmeier, East Aurora, N.Y., assignor to
Birdair Structures, Inc., Buffalo, N.Y.
Filed Apr. 14, 1961, Ser. No. 102,991
3 Claims. (Cl. 24—203)

This invention relates to joining means for flexible panels subjected to tension and pertains more particularly to means for quickly attaching and detaching flexible panels such as are used in fabric building structures such as air-inflated structures, tent-like structures and the like.

The use of fabric building structures is becoming more and more pronounced. For example, in military fields, such structures find frequent application by reason of the fact that a relatively large structure may be erected in a relatively short period of time, the components thereof being subject to easy storage and being characterized by compactness so as to be readily transportable. Such structures may be in the form of relatively large panels of flexible, substantially impervious material which will ultimately be joined together to provide a skin or enclosure which is characterized by tensioning of the fabric or flexible material to rigidify the same and render it load-sustaining. It is to be understood that the present invention is not limited to any specific type of fabric structure although the invention is admirably suited for association with fabric structures of the air-inflated type.

Having the above in mind, it will be readily apparent that one of the advantages of fabric structures is their ability to be rather rapidly erected and it is to this end that the present invention is directed. That is to say, it is of primary concern in connection with the present invention to provide an improved and novel fastening means for joining the adjacent panels or sections of a fabric structure together and to do so in such fashion that the flexible material or sections will be efficiently joined so as to permit uniform distribution of tension loads between adjacent panels or sections of the structure without imposing localized stress concentrations in the sections or panels such as would tend to occasion their ultimate damage or destruction.

The present invention constitutes an improvement in such fastening means as are disclosed in application Serial No. 739,022, filed June 2, 1958, and the present invention seeks to provide an improved panel or section joining means which is characterized by the rapidity of its attachment or detachment so as to increase the overall efficiency of tensioned fabric, load-sustaining structures and to render the same more readily adaptable for use in many applications.

A further object of the present invention resides in the provision of an improved joining means for adjacent sections of a tensioned-fabric, load-sustaining structure wherein in addition to permitting of quick attachment and detachment of such sections, the same will render the initial cost of the structure of a more economical nature.

More specifically, it is an object of the present invention to provide an improved form of section or panel attaching means particularly as adapted for joining adjacent sections subjected to tension loads wherein the adjacent sections are characterized by having a series of spaced loops formed along their edges to be joined wherein the loops are of substantially the same width as the spacing between adjacent loops and wherein the loops carry peg means which project from opposite sides thereof so that the panels to be joined may be interlaced by interdigititation of the pegs of one panel with the pegs of an adjacent panel to form thereby a continuous, but quickly detachable seam for transferring the tension loads between the panels or sections thus joined.

2

For a better understanding of this and other objects of the invention, reference is made to the following specifications and accompanying drawings wherein:

FIG. 1 is a sectional view showing a portion of an edge of a flexible panel constructed in accordance with the present invention and illustrating the means by which two adjacent such panels may be joined;

FIG. 2 is a view showing the manner in which a pair of panels may be interlaced or joined;

FIG. 3 is a plan view showing portions of a pair of adjacent panels which have been joined and are ready for erection; and

FIG. 4 is an enlarged sectional view taken substantially along the plane of section line 4—4 in FIG. 3 and illustrating means by which a seal may be accomplished across the seam or joint.

Referring now more particularly to FIG. 1, the reference character 10 therein designates generally a flexible panel or section of a tensioned-fabric, load-sustaining structure which is in the form of a body or panel of substantially impervious and flexible material 12 and which forms a portion of a load-sustaining fabric structure. Reference character 14 designates an edge portion of the panel 10 which is desired to be joined to an adjacent panel similarly formed. This edge portion is formed with a series of loops 16 and intervening notches 18 wherein the width of the notches 18 is at least equal to the width of the loops 16 to permit interdigititation of the loops of adjacent panels such as are designated generally as reference characters 20—22 in FIG. 3.

Loop 16 carries a peg or pin 24 which has opposite end portions 26 and 28 projecting laterally from the opposite ends of the respective loops 16 to terminate short of the corresponding adjacent ends of the next sequential pegs. These pegs 24 may be secured within the loops by any suitable means as for example by staples 30 which serve only the purpose of retaining the pegs within the loops to prevent loss of the pegs. Preferably, such securing means are in the form of some mechanism which is easily removable so as to permit field replacement of pegs should they become damaged or broken.

The manner of assembly of the joint is illustrated in FIG. 2 wherein it will be readily appreciated that the construction lends itself readily to the lacing together of the panels 20 and 22 generally in the fashion indicated therein. That is to say, the end 32 of the next peg to be joined is placed behind the end 34 of the last peg joined and then the other end 36 of this peg is then swung up into position so as to interlace behind the end 38 of the next peg and so on until the joint is completed. It will be appreciated also that the loops 16, since they are relatively short, even though they are rigidified by their associate pegs 34, do not constitute a great distraction from the flexibility of the individual panels or sections and present no problem in the folding and storing of these individual sections. At the same time there is no necessity for any separate mechanism, physically removable from the panels, to provide the requisite joint, and for this reason alone the present mode of construction is readily adaptable for quick assembly as has been described.

A completed joint portion is shown in FIG. 3 and a section therethrough is illustrated in FIG. 4. It will be appreciated that FIG. 4, insofar as the construction of the panels 20 and 22 are concerned, is largely diagrammatic and purely illustrative and is not intended to show the specific details or their individual constructions other than to show the retention of the pegs 24. In accordance with the copending application previously mentioned, the marginal edge portions 14 of the panels, see FIG. 1, are so constructed as to quickly dissipate the localized tension loads imposed on the separate loops into uniformly

distributed stress loads in the fabric or material of the panel longitudinally along the seam, thus obviating localized stress concentrations in the panels or sections such as would tend to destroy them. In regard to this, it may be noted that actual structures utilizing this type of joining means have been designed to withstand tension loads equal to 750 pounds per inch, in which case the pegs 24 were constructed of hard wood dowels having a diameter of $\frac{5}{8}$ inch. Under the above conditions, when the present invention is utilized in association with the proper construction of the marginal edge portion 14 so as to dissipate the localized stresses as aforesaid, actual tests have shown that $\frac{5}{8}$ inch hard wood dowels will fail before the fabric is subjected to such loading as will tear or rip the same.

At the same time it will be readily appreciated that should a peg 24 be damaged or broken it is a simple matter to remove the fastening means 30 and to insert a new peg. This type of operation is easily performed in the field and constitutes a further advantage of the present invention.

FIG. 4 illustrates a simple means of obtaining a good seal along the joint. This seal takes the form of a flexible strip of material 40 which is permanently secured, as by bonding, stitching or the like, along one edge 44 thereof to one panel 22, the other edge 43 of the strip being detachably secured by suitable fasteners 42, preferably snap fasteners, and is adapted to overlie the joint substantially as shown.

In accordance with the present invention, it will be seen that rapidity in both attachment and detachment is of primary concern, without sacrificing the uniform tension load-transfer between panels or sections. FIG. 2 illustrates how the sections are easily joined with great rapidity. The problem of detachment is actually more simple inasmuch as several pegs may be sequentially disengaged without moving the point of gripping of the hands on the section. This is accomplished by first gripping the two sections near the end of the joined seam and then manipulating the wrists and hands in relatively opposite directions while maintaining the fabric in tension by gradually separating the hands as successive pegs are released. This is repeated along the length of the seam.

Further in regard to this, it will be appreciated that structure with which this invention may be associated are normally quite large so that the cumulative length of all seams required may be surprisingly substantial. Purely as an example, present air-inflated structures may encompass a span of 60 feet and have a length of 100 feet. Clearly, such a structure, of necessity incorporating several panels or sections, will realize substantial time saving both in erection and disassembly by means of the fastening technique according to this invention.

At the same time, it will be appreciated that the fastening means according to the present invention is not

subject to damage by corrosion, freezing or clogging and in all respects represents means relatively impervious to weather conditions in its operation and manipulation.

What is claimed is:

1. The combination, in a tensioned-fabric, load-sustaining building structure including at least a pair of separate flexible sections adapted to be quickly joined to cumulatively form an integral load-sustaining portion, of means for effecting the quick attachment and detachment of such sections, the two sections having mating marginal edge portions, said means comprising a series of spaced, rectangular plan view loops formed along each marginal edge in which the spacing between adjacent loops is at least as great as the width of an individual loop, a rigid peg positioned transversely within the free end of each loop and being fixed thereto, each peg being of a length greater than the width of the loop so that the opposite ends extend therebeyond for interdigititation of the pegs of one section with the pegs of the other section.
2. In a tensioned-fabric, load-sustaining building structure, a pair of flexible panel sections having mating edge portions, each such edge portions presenting a continuous series of spaced, rectangular plan view loops therealong defining intervening notches, the width of each loop, between adjacent notches, being less than the width of the notches and the loops of the two edge portions being interdigitated with each other, a rigid peg captive in the free end of each loop, and each peg being of a length to extend beyond the opposite sides of its associated loop to overlap and lie behind peg-filled loops of the other section immediately thereadjacent.
3. In a tensioned-fabric, load-sustaining building structure, a pair of flexible panel sections having mating edge portions, each such edge portion presenting a continuous series of spaced loops therealong defining intervening notches, the width of each loop, between adjacent notches, being less than the width of the notches and the loops of the two edge portions being interdigitated with each other, a peg captive in each loop, and each peg being of a rigid length to extend beyond the opposite sides of its associated loop to overlap and lie behind peg-filled loops of the other section immediately thereadjacent, the diameter of each loop being such that said opposite ends of each associated peg lie closely adjacent the edges of the adjacent notches.
